UNITED STATES PATENT OFFICE

2,457,317

WINDOW CLAMP

Marvin R. Olsen, Glen Ellyn, Ill., assignor to Just-
rite Manufacturing Company, Chicago, Ill., a
corporation of Illinois

Application March 14, 1946, Serial No. 654,339

4 Claims. (Cl. 292—76)

1

The invention relates to tension devices and has particular reference to an improved window clamp of simple construction, capable of applying tension to a window frame for preventing a rattle and other noise caused by a loose fitting of said frame in its window jamb.

An object of the invention resides in the provision of a clamp or similar device for application to window frames and which will provide tension means of a resilient nature for preventing noise caused by rattling of the window frame.

The anti-rattling device of the invention has a curved central section on a leg portion thereof forming a resilient part of arcuate shape and which is compressed between the window frame and the jamb when the device is inserted in the space between these elements. The action of fastening the device to the window frame functions to embed the prongs provided by the device in the window frame, and thus the parts are maintained in secured relation during operation.

Another object of the invention is to provide a metal clamp as above described having means for readily securing the same to a window frame and which will function in a manner that assists in retaining the clamp in operative position on the frame.

With these and various other objects in view, the invention may consist of certain novel features of construction and operation, as will be more fully described and particularly pointed out in the specification, drawings and claims appended hereto.

In the drawings which illustrate an embodiment of the device and wherein like reference characters are used to designate like parts—

Figure 1 is a perspective view of a tensioning device constructed in accordance with the present invention;

Figure 2 is an elevational view, parts being shown in section, to illustrate the location and manner of securing the device to a window frame;

Figure 3 is a sectional view taken along line 3—3 of Figure 2 showing the device in front elevation;

Figure 4 is a fragmentary elevational view of a window frame showing another adaptation of the present window clamp; and

Figure 5 is a sectional view taken substantially along line 5—5 of Figure 4.

Referring to the drawings, the tensioning device or window clamp selected for illustrating the present invention is shown in perspective in Figure 1 and which view clearly illustrates the several constructional features comprising the

present improvements. The said device is preferably formed from a single strip of spring metal of any desired width, primarily depending on the type of frame to which the device is to be applied. The metal strip is bent to form a leg portion 10 and a right angle flange portion 11. The leg portion is characterized by the curved section 12 and by the end sections 13 and 14. The free end 14 is provided with a punched opening 15 and the metal below the opening is separated and bent to form an inwardly directed prong 16.

The sections 13 and 14 of the metal strip located above and below the arcuate section 12, respectively, are bent so as to lie in substantially the same plane at least when pressure is applied to the arcuate section 12 as is evident from an inspection of Figure 2. The leg portion 10 is terminated by the right angle bend 17 forming the top flange 11. Said top flange is additionally bent to provide the depending securing spike 18. The spike 18 is accordingly located in spaced parallel relation as regards the leg portion and the distance between the parts depends on the length of the top flange 11. In order to facilitate entrance of the spike 18 into the frame of a window or the like, the same is formed in the shape of an arrow having the pointed end 19.

As shown in Figure 2, the anti-rattling device of the invention has been applied to the lower window frame 20, the frame structure of which is formed in part by top horizontal member 21, a side vertical member 22, and the glass pane 23. The lower frame is disposed in associated relation with an upper frame indicated generally by 24 and which includes the vertical frame member 25 and the glass pane 26. The window frames are located within the window opening provided in part by vertical side members such as 27 which comprise the window jamb and which provide the channels 28 and 30 for receiving the lower and upper window frames, respectively. The partition member 31 separates channel 28 from channel 30 and the frames are accordingly positioned on the respective sides of this partition member.

Upon insertion of the present window clamp in the space between the window frame and the window jamb, the same will be subjected to pressure and which is applied against the resilient section 12. In the manufacture of the window clamp, it is desirable that the resilient section 12 have sufficient curvature, which, however, may be limited in extent so that the device will at all times provide the desired tension when inserted between frame members such as the lower window and jamb, as shown in Figure 2.

Following the insertion of the device between said frame members, securement of the same to the window frame is accomplished by embedding the spike 18 in the frame 21. The arrowhead shape of the spike facilitates insertion in the wood frame member 21, and although entrance is thus facilitated, nevertheless, it is extremely difficult to retract or remove the device from its secured position on the frame. The retaining action of spike 18 is supplemented by the prong 16, which prong is bent inwardly, being located out of the plane of the free end section 14. The action of prong 16 in embedding itself in the wood of frame member 22 is practically automatic and results from the insertion of the device between the window frame and the jamb which causes pressure to be applied to the arcuate section 12. This pressure tends to flatten the arcuate section with the result that sufficient pressure is applied to the depending end 14 to cause prong 16 to embed itself in the window frame.

It is entirely possible to apply one or more of the anti-rattling devices of the invention to a single window frame, one being applied at each corner, for example. The tension exerted by the resilient section 12 is maintained during movement of the window frame and also in all locations vertically, to which the frame may be opened. Any rattling of the frame and other noise due to a loose fit of the frame is eliminated. It is also possible for the present device to have a limited sealing function by sealing off the space between the window frame and its jamb.

The most important feature, however, is the uniform application of tension to eliminate noise and rattle, and which tension may be sufficient in many cases to provide the necessary friction against free and easy movement of the window, thereby counteracting to a degree at least the counterbalancing function of the conventional window weights.

It will be observed that the spike 18 and the prong 16 are directed toward each other in opposed relation. Their action is to retain the device in secured relation on the window frame, since when the window is moved downwardly the prong 16 is effective as a fastening element and when moved upwardly the action is to assist in maintaining the spike 18 in its embedded relation in the frame.

In Figure 4 the window clamp of the invention has been secured to the lower window frame and located between the inside molding 32. As a result the window frame is yieldingly urged outwardly and held in contact with partition member 31. The bottom horizontal frame member 33 of the lower window frame is suitably secured to the side vertical member 22 for retaining the glass pane 23. To prevent transverse movement of the window frame, the window clamp has been applied to the front surface of frame member 33, being located between the member and the inside molding 32. The device is applied in a manner as described, that is, by embedding the spike 18 in the frame member, which securely holds the device in place on the window frame, preventing inadvertent removal of the device even when the window is moved upwardly in an opening direction. The retaining action of spike 18 is supplemented by prong 16 which automatically embeds itself in the front surface of frame member 33. The arcuate and resilient portion 12 of the present tensioning device is thus positioned between the window frame and the inside molding 32 to apply pressure to the molding and to thus yield-

ingly force the window frame into contact with partition member 31. Any tendency of the device to rattle caused by movement of the window frame transversely of channel 28 is effectively prevented and the action of the tensioning device also facilitates the sealing of the window frame since close contact is maintained with the partition member 31.

The invention is not to be limited to or by details of construction of the particular embodiment thereof illustrated in the drawings, as various forms of the device will of course be apparent to those skilled in the art without departing from the spirit of the invention or the scope of the claims.

What is claimed is:

1. In an anti-rattling device for windows and the like, an integral strip of metal, including a leg portion and a right angle flange portion at one end of the leg portion, an arcuate section formed in the leg portion by bending the same outwardly centrally thereof in a direction opposite to that of the flange portion, securing means provided by the flange portion and comprising a spike disposed at right angles to the flange portion and having a spaced parallel relation with the leg portion, and said leg portion having a prong bent from the metal thereof forming additional securing means.
2. In an anti-rattling device for windows and the like as defined by claim 1, wherein the spike and said prong extend toward each other in opposed relation.
3. In an anti-rattling device for windows and the like as defined by claim 1 wherein said prong is located adjacent the end of the leg portion opposite the said flange portion, and wherein the spike and said prong extend toward each other in opposed relation.
4. A window clamp for operative association with a movable window frame and an upright member of the jamb defining the window opening, comprising a one-piece metal strip having a leg portion and a right angle flange portion at one end of the leg portion, an arcuate resilient section formed in the leg portion by bending the metal thereof outwardly in a direction opposite to that of the flange portion, said flange portion providing securing means for fastening the metal strip to the window frame with the leg portion disposed between the frame and said upright member, said securing means comprising a spike having a right angle relation with the flange portion, and said leg portion having a prong bent from the metal thereof forming additional securing means for fastening the metal strip to the window frame, said spike and prong extending toward each other in opposed relation.
